(57) **CLAIM**

The ornamental design for a self-engaging bundling strap provided with machine readable code, as shown and described.

DESCRIPTION

FIG. 1 is a perspective view of a self-engaging bundling strap provided with machine readable code showing our new design in use;

FIG. 2 is a perspective view of a self-engaging bundling strap provided with machine readable code showing our new design in use;

FIG. 3 is a fragmentary top view thereof;

FIG. 4 is a bottom view thereof;

FIG. 5 is a side view thereof;

FIG. 6 is a end view;

FIG. 7 is a end view; and,

FIG. 8 is a full top view of a self-engaging bundling strap provided with machine readable code.

The broken lines showing the fastener elements in FIGS.1-8 is for illustrative purposes only and forms no part of the claimed design.
